UNITED STATES PATENT OFFICE.

CARL SJOMAN, OF RAMSAY, MICHIGAN.

SELF-CLEANING CURRYCOMB.

Application filed September 2, 1921. Serial No. 497,973.

To all whom it may concern:

Be it known that I, CARL SJOMAN, a citizen of the United States, residing at Ramsay, in the county of Gogebic, State of Michigan, have invented a new and useful Self-Cleaning Currycomb; and I do hereby declare the following to be a full, clear, and exact description of the invention, such as will enable others skilled in the art to which it appertains to make and use the same.

The invention relates to currycombs and has for its object to provide a device of this character wherein longitudinally disposed plates carried by a frame are pivotally connected to one end of the flanged members having the currycomb teeth and spaced inwardly from said teeth, and adapted to be moved downwardly on their pivotal points simultaneously for cleaning the currycomb teeth thereby obviating damage to the currycomb incident to knocking the same against a support. Also to provide means whereby the cleaning frame at its free end may be secured to the main body of the currycomb.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit 35 of the invention.

In the drawings:—

Figure 1 is a perspective view of the currycomb showing the cleaning frame in lowered position after a comb cleaning 40 operation.

Figure 2 is a side elevation of the currycomb, part of the cleaning frame being broken away to better show the structure.

Referring to the drawing, the numeral 1 45 designates currycomb, which comb is formed from a rectangular shaped plate 2, the opposite sides of which are provided with downwardly extending right angularly disposed flanges 3, the lower edges of which are provided with teeth 4 which scrape over the skin of the animal and dislodge dirt. Secured to the plate 2 and to its under face are spaced angle members 5, having downwardly extending flanges 6, the lower edges 55 of which are provided with teeth 7, which teeth are similar to the teeth 4 and are

preferably disposed in the same plane. Secured to the plate 2 by means of rivets 8 is a handle member 9 adapted to be grasped by the operator during a combing operation. It has been found that the teeth 4 and 7 become clogged with hair and dirt, and that the same interferes with the efficient operation of the comb as a whole. It is the present practice to hit the comb 60 against a support for dislodging the hair and dirt. The above hitting operation not only damages the comb, but it does not dislodge the dirt and hair, as said dirt and hair contain a great deal of oil from the 70 body of the animal. To accomplish the above cleaning operation without damaging the comb, a cleaning frame 10 is provided. The frame 10 comprises a U-shaped frame 11 having secured to its transverse portion 75 12 spaced cleaning bars 13, which cleaning bars engage the sides of the flanges 6 and when the frame 10 which is pivoted at 14 and 15 to the flanges 3 and 6 is forced downwardly at its free end, the bars 13 will 80 scrape the sides of the flanges 2 and force the hair and dirt which may collect on the lower edges of the flanges 6 from said flanges. The arms 16 of the U-shaped frame 11 scrape the faces of the end flanges 3 85 80 thereby maintaining them clean. During a combing operation the frame 10 is in closed position as shown in Figure 2 and held in said position by means of a hook 17 which engages over a lug 18 carried by the plate 2. 90

From the above it will be seen that a cleaning device is provided for a currycomb which is simple in construction positive in its operation, and one wherein the parts have been reduced to a minimum thereby allowing the device to be cheaply constructed.

The invention having been set forth what is claimed as new and useful is:—

The combination with a currycomb having a plurality of spaced toothed flanges in parallel relation to each other, of means for cleaning said teeth, said means comprising a U-shaped frame having its arms pivoted in axial alignment to each other to the 100 outer toothed flanges of the currycomb, U-shaped members forming spaced parallel bars, said parallel bars being pivoted to the toothed flanges the transverse portion of said last named U-shaped members being 105 secured to the transversely disposed portion of the first mentioned U-shaped frame,

said bars and arms of the U-shaped members forming means for scraping the sides of the toothed flanges when they are moved downwardly at their free ends, and means 5 for locking the cleaning device as a whole in a closed position.

In testimony whereof I have signed my

name to this specification in the presence of two subscribing witnesses.

CARL SJOMAN.
